(57) **CLAIM**

The ornamental design for an ergonomic seam ripper, as shown.

DESCRIPTION

FIG. 1 is a perspective view of an ergonomic seam ripper with a transparent removable cover;

FIG. 2 is a front view of the ergonomic seam ripper of FIG. 1;

FIG. 3 is a back view of the ergonomic seam ripper of FIG. 1;

FIG. 4 is a right side view of the ergonomic seam ripper of FIG. 1;

FIG. 5 is a left side view of the ergonomic seam ripper of FIG. 1

FIG. 6 is a top view of the ergonomic seam ripper of FIG. 1; and,

FIG. 7 is a bottom view of the ergonomic seam ripper of FIG. 1.

Oblique line shading indicates a transparent cover for the forked seam ripper member.

1 Claim, 6 Drawing Sheets
